UNITED STATES PATENT OFFICE.

ARTHUR H. MOTT, OF WINSTON-SALEM, NORTH CAROLINA.

DOOR-BOLT.

1,377,091.

Specification of Letters Patent.

Patented May 3, 1921.

Application filed December 9, 1918. Serial No. 265,976.

To all whom it may concern:

Be it known that I, ARTHUR H. MOTT, a subject of the King of Great Britain, residing at Winston-Salem, in the county of 5 Forsyth and State of North Carolina, have invented new and useful Improvements in Door-Bolts, of which the following is a specification.

This invention relates to new and useful 10 improvements in doors and the principal object of the invention is to provide means for automatically withdrawing the locking bolt of the door by the weight of a person attempting to pass through the doorway in 15 one direction.

The invention also consists in certain other 20 features of construction and in the combination and arrangement of the several parts, to be hereinafter fully described, illustrated 25 in the accompanying drawings and specifically pointed out in the appended claim.

In describing my invention in detail, reference will be had to the accompanying 25 drawings wherein like characters denote like or corresponding parts throughout the several views, and in which:—

Figure 1 is an elevation of the invention.

Fig. 2 is a transverse section.

Fig. 3 is an enlarged view of the locking 30 means.

The invention is more particularly adapted for swinging doors used in "serve self" stores, moving picture theaters and the like, where a door is required at the entrance or exit which will admit of passage 35 in but one direction.

In the drawings, 1 indicates the swinging door and 2 the jam. 3 indicates a lock casing located in the jam, and containing the bolt 40 4 sliding in the guides 5 and held in projected position by the spring 6. 7 indicates a bell crank lever pivoted in the casing and having its pawl shaped end engaging with the rear rounded end of said bolt. If desired the bolt may be secured to said end by means of a link 8. The other part of the lever is provided with a slot 9 and a link 45 10 has one end engaging said slot and its other end connected to a rod 11 carried by 50 the movable platform 12. This movable

platform forms part of the floor in front of the door, and said platform has its end farthest from said door secured to a shaft 13 which is journaled in suitable bearings secured to the floor. Springs 14 under the 55 platform hold the same in its uppermost position and plates 15 secured to the floor and projecting into the path of movement of said platform prevent the same from rising above the level of the floor. 60

It will thus be seen that when a person steps on the platform his weight will overcome the springs so that the platform will be lowered. This movement of the platform will rock the bell crank lever so as to retract the bolt from the keeper on the door 65 so as to permit the door to swing open. When the person passes through the doorway the springs will return the platform to normal position and the bolt will be forced 70 into projecting position. Thus when the door swings shut it will be engaged and locked by the bolt. In this way a person can pass through the doorway from one direction only. 75

It is thought from the foregoing description that the advantages and novel features of my invention will be readily apparent.

I desire it to be understood that I may make changes in the construction and in the 80 combination and arrangement of the several parts, provided that such changes fall within the scope of the appended claim.

I claim as my invention:

In combination with a swinging door and 85 a spring controlled locking bolt therefor, a hinged platform located adjacent said door, a stationary plate secured to the floor and arranged to engage the platform to limit the upward movement of the same, a spring 90 under the platform for normally holding the same against the plate, a bell crank lever mounted in the bolt casing and having one arm connected to the bolt and a slot in its other arm and a link connected with the 95 platform and its other end engaging said slot.

In testimony whereof I affix my signature.

ARTHUR H. MOTT.
